US0D1075316S

(12) **United States Design Patent** (10) **Patent No.:** **US D1,075,316 S**
(45) **Date of Patent:** **** May 20, 2025**

(54) **PAPER SHEET**

(71) Applicant: **Kimberly-Clark Worldwide, Inc.,**
Neenah, WI (US)

(72) Inventors: **Danelle M. Buyarski**, De Pere, WI
(US); **Jason D. Hanke**, Appleton, WI
(US); **Eric B. Maclean**, Neenah, WI
(US); **Sarah M. McGinnis**, Appleton,
WI (US)

(73) Assignee: **Kimberly-Clark Worldwide, Inc.,**
Neenah, WI (US)

(**) Term: **15 Years**

(21) Appl. No.: **29/833,446**

(22) Filed: **Apr. 4, 2022**

(51) LOC (15) Cl. **05-06**
(52) U.S. Cl.

USPC **D5/55; D5/57**

WORLDWIDE, INC.

(57) **CLAIM**

The ornamental design for a paper sheet as shown and described herein.

DESCRIPTION

The sole FIGURE is a top plane view of a paper sheet showing our new ornamental design.

The dot-dot-dash broken lines in the sole FIGURE show an unclaimed boundary which forms no part of the claimed design. The evenly dashed broken lines show surface pattern and do form part of the claimed design.

1 Claim, 1 Drawing Sheet
